US00D963152S

(12) **United States Design Patent** (10) **Patent No.:** **US D963,152 S**
Smith (45) **Date of Patent:** **** Sep. 6, 2022**

(54) **FLEXIBLE COVER AND AIR GRILLE COMBINATION**

(71) Applicant: **Brian D. Smith**, Highlands Ranch, CO (US)

(72) Inventor: **Brian D. Smith**, Highlands Ranch, CO (US)

(73) Assignee: **Unlocked Technologies LLC**, Highlands Ranch, CO (US)

(**) Term: **15 Years**

(21) Appl. No.: **29/764,787**

(22) Filed: **Jan. 2, 2021**

Related U.S. Application Data

(63) Continuation of application No. 15/899,388, filed on Feb. 20, 2018, now abandoned.
